UNITED STATES PATENT OFFICE.

WILLIAM S. SCHROEDER AND ANDREW P. LINDHOLM, OF CHICAGO,
ILLINOIS, ASSIGNORS TO CHARLES H. FERRY, OF CHICAGO, ILLINOIS.

CAR-COUPING.

No. 807,582.

Specification of Letters Patent.

Patented Dec. 19, 1905.

Application filed April 6, 1905. Serial No. 254,101.

To all whom it may concern:

Be it known that we, WILLIAM S. SCHROEDER and ANDREW P. LINDHOLM, citizens of the United States, residing in Chicago, in the county of Cook and State of Illinois, have invented a new and useful Improvement in Car - Couplers, of which the following is a specification.

Our invention relates to improvements in car-couplers of the Master Car-Builders' type having a forked draw-head, a pivoted knuckle, and a gravity-lock, and more particularly to improvements upon the car-coupler forming the subject of our Patent No. 780,235, dated

January 17, 1905.

Our invention consists in an improved construction of the lock-set devices employed in our said former patent, No. 780,235, and by which certain difficulties in the operation of the coupler are overcome, the same comprising certain novel constructions and novel combinations of parts and devices herein shown and described, and particularly specified in the claims.

In the accompanying drawings, forming a part of this specification, Figure 1 is a central vertical section of a longitudinal pivotal locking-bar coupler embodying our invention. Fig. 2 is a similar view showing the locking-bar in its raised or lock-set position—that is to say, when the coupler is set for uncoupling. Fig. 3 is a horizontal section on line 3 3 of Fig. 1. Fig. 4 is a plan view, partly in section, on line 4 4 of Fig. 1. Fig. 5 is a vertical cross-section on line 5 5 of Fig. 1. Fig. 6 is a detail perspective view of the locking or lifting pin. Fig. 7 is a side elevation of the longitudinal pivotal locking-bar. Fig. 8 is a front end view of the same. Fig. 9 is a detail view of the knuckle-throwing lever. Fig. 10 is a detail front view of the knuckle, and Fig. 11 is a detail plan view showing the opening in the draw-head for the lifting-pin.

In the drawings, A represents the draw-bar; A', the forked draw-head having the customary pivot-arm A² and guard-arm A³.

B is the knuckle, pivoted to the draw-head by the pivot-pin C and having a tail B', which is engaged by the longitudinal pivotal locking-bar D, which fits and lies in the chamber a of the draw-bar and which has not only a pivotal movement to enable its

front end to be raised, but also a slight longitudinal movement bodily forward to enable its lock-set projection to properly engage the lock-set projection or ledge on the draw-bar. The tail B' of the knuckle has at its rear end a transversely-extending inclined face b to engage the curved or inclined face d of the locking-bar D, and thus automatically lift the locking-bar by the closing movement of the knuckle, the inclined face of the knuckle-tail thus passing under the locking-bar.

The locking-bar D has near the front end thereof and on one side thereof a lock-set projection d', furnished with an inclined end face d² and with a slight notch or recess d³ on its lower edge adapted to engage a lock-set projection or ledge a' on the draw-bar A. The pivotal and longitudinally-movable locking-bar D is also provided near its front end with a lug or projection d⁴ on its lower face, said lug having an inclined rear face d⁵ engaging a correspondingly-inclined face a² of the recess a³ in the draw-bar in which said lug or projection d⁴ fits. The inclined face of this downwardly-projecting lug d⁴, in connection with the inclined face of this recess a³, aids in throwing the lock forward into its proper position when the locking-bar drops.

F is the coupling or lifting pin, by which the outer or free end of the longitudinally-extending pivotal locking-bar D is operated or lifted to unlock the coupler or permit the knuckle to swing open.

F' is a clevis pivotally connected to the upper end of the lifting-pin F and connected by a link F² and clevis F³ with the lifting-lever F⁴, and G is the knuckle-throwing lever.

The draw-bar is provided inside the chamber a on its lower web or floor with integral saddles or ribs a⁴, having elongated pivot-notches or recesses a⁵ therein to receive the pivot-lugs d⁷ at the rear end of the locking-bar D, the pivot notches or slots a⁵ being long enough to permit the necessary longitudinal movement of the locking-bar to enable its lock-set lug or projection d' to engage the corresponding lock-set lug or projection a' on the tail of the knuckle. The elongated notch or recess a⁵ has an inclined bottom a⁶, which aids in returning the locking-bar longitudinally to position when in its forward position, and thus also diminishing the inclina-

tion of the pivotal locking-bar when its front end is raised to its lock-set position on the knuckle-tail.

The locking-bar D is provided at its front end with a chamber d^8 , having an opening d^9 large enough to receive the head or shoulder f on the coupling or lifting pin F and provided with a slot d^{10} to receive the shoulder f' , which connects the head or shoulder f with the coupling-pin F.

The draw-bar A is provided with a guide-rib a^7 to engage the front or enlarged end of the locking-bar D to keep the same in position laterally, which permits the locking-bar to be raised as required at its front end. The lifting-pin F fits in an opening a^8 in the top wall a^9 of the draw-head and is provided with an irregularity or rib f^2 , which prevents its being turned wrong when it is put in place. To cause the locking-bar D to be thrown or moved longitudinally forward as it is raised by the lifting-pin F, the draw-head is provided with a projection or fulcrum a^{10} to cause the upper end of the lifting-pin to tilt backward and its lower end forward when the lifting-pin is acted upon by the lifting-lever F⁴. To further insure the proper backward tilting of the lifting-pin and the longitudinal forward movement of the locking-bar when the same is being raised, we provide the clevis F' with an arm f^3 , which engages a flange f^4 of the lifting-pin, and thus limits the pivotal movement of the clevis on the pin. The projecting arm on the clevis also prevents any possibility of the links of the lifting-chain becoming kinked or entangled.

To set the locking-bar in its position for permitting the cars to uncouple when the two adjacent cars are separated, the locking-bar is raised or lifted by the lifting-lever through the lifting-pin F, this operation simultaneously moving the locking-bar slightly longitudinally forward, so that its lock-set lug d' will engage and rest upon the lock-set lug a' on the draw-bar, and thus hold the lock in its raised or lock-set position. When the coupled cars are now pulled apart, the tail of the knuckle rides under the lock, now held in its raised or unlocking position, and thus permits the cars to uncouple.

The knuckle-throwing lever G has a pivot arm or projection g , which fits in a suitable notch or recess a^{11} in the draw-head, and an actuating web or arm g' , which fits over the front end of the locking-bar D and is engaged thereby when the front end of the locking-bar is sufficiently lifted. The knuckle-throwing lever G also has a curved or horn-shaped arm g^2 , which engages and follows the tail of the knuckle to throw the same open. The knuckle-throwing lever has both a rocking or rotary movement about its pivot-arm g as an axis and also a swinging or tilting movement about the extreme end of its pivot-arm g as a fulcrum, thus giving the curved or horn-shaped

operating-arm g^2 , which engages the knuckle, a combined or compound movement that causes it to properly follow the path of the tail of the knuckle in pushing or throwing the knuckle open. When the flat arm g' of the knuckle-throwing lever g is engaged by the front end of the locking-bar D as it moves upward, it tends to tilt or swing the knuckle-throwing lever about the end of its pivot-arm g as a fulcrum for the lever and at the same time to rock or rotate the knuckle-throwing lever about its arm g as an axis, thus giving its curved or horn-shaped operating-arm g^2 a compound movement, the resultant of these two motions of the lever causing the knuckle-throwing lever, though mounted above the knuckle, to keep its curved arm g^2 in proper engagement with the tail of the knuckle as it swings open in its horizontal circular path. To cause the flat or web arm g' of the knuckle-throwing lever G to be properly engaged by the locking-bar D, the locking-bar is provided at its front end with a wing or projection d^{11} , that engages the web or flat arm of the knuckle-throwing lever after the front end of the locking-bar is raised sufficiently to permit the tail of the knuckle to move under the same. The chamber a in the draw-head for the arm g^2 of the knuckle-throwing lever G has a rib a^{12} extending across it to serve as a guide, rest, and support for the knuckle-throwing lever.

We claim—

1. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, substantially as specified.

2. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, said lock-set lug or projection on the side of the locking-bar having an inclined face, substantially as specified.

3. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, said lock-set lug or projection on the side of the locking-bar having an inclined face, and said lock-set lug or projection on the locking-bar having a notch or recess in its lower edge, substantially as specified.

4. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, said locking-bar being provided with a lug or projection on its under side having an inclined face, and said draw-bar having a recess to receive said lug or projection on the lower side of the draw-bar, substantially as specified.

5. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, said locking-bar being provided with a lug or projection on its under side having an inclined face, and said draw-bar having a recess to receive said lug or projection on the lower side of the draw-bar, substantially as specified.

6. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, said lock-set lug or projection on the side of the locking-bar having an inclined face, and said lock-set lug or projection on the locking-bar having a notch or recess in its lower edge, said locking-bar being provided with a lug or projection on its under side having an inclined face, and said draw-bar having a recess to receive said lug or projection on the lower side of the draw-bar, substantially as specified.

7. In a car-coupler, the combination with a pivoted knuckle, a forked draw-head, and a draw-bar having a chamber to receive a longitudinal pivotal locking-bar, of a pivotal and longitudinally-movable locking-bar lying lengthwise in the chamber of the draw-bar, and provided near its front end on one side thereof with a lock-set lug or projection, a coupling or lifting pin connected with the front or free end of the locking-bar, said draw-bar having a lock-set lug or projection to engage the lock-set lug or projection on the side of the locking-bar when the same is raised and moved longitudinally forward by the lifting-pin, said locking-bar being provided with a lug or projection on its under side, having an inclined face, and said draw-bar having a recess to receive said lug or projection on the lower side of the draw-bar, and said recess in said draw-bar having an inclined face to further aid in moving said locking-bar longitudinally forward, substantially as specified.
